CLAIM

The ornamental design for a disposable mitt, as shown and described.

DESCRIPTION

FIG. 1 is a top plan view of a first embodiment of a disposable mitt;

FIG. 2 is a bottom plan view thereof;

FIG. 3 is a front elevational view thereof, wherein the rear elevational view is identical thereto; and

FIG. 4 is a left side elevational view thereof, wherein the right side elevational view is identical thereto.

FIG. 5 is a top plan view of a second embodiment of a disposable mitt, with the bottom plan view, front/rear elevational views, and left/right elevational views thereof being identical to the corresponding bottom plan view, front/rear elevational views, and left/right elevational views of the first embodiment of FIGS. 1-4.

FIG. 6 is a top plan view of a third embodiment of a disposable mitt, with the bottom plan view, front/rear elevational views, and left/right elevational views thereof being identical to the corresponding bottom plan view, front/rear elevational views, and left/right elevational views of the first embodiment of FIGS. 1-4.

FIG. 7 is a top plan view of a fourth embodiment of a disposable mitt, with the bottom plan view, front/rear elevational views, and left/right elevational views thereof being identical to the corresponding bottom plan view, front/rear elevational views, and left/right elevational views of the first embodiment of FIGS. 1-4.

FIG. 8 is a top plan view of a fifth embodiment of a disposable mitt, with the bottom plan view, front/rear elevational views, and left/right elevational views thereof being identical to the corresponding bottom plan view, front/rear elevational views, and left/right elevational views of the first embodiment of FIGS. 1-4.

(Continued)

front/rear elevational views, and left/right elevational views of the first embodiment of FIGS. 1-4.
